DISK BIT

John H. Howard, Huntington Park, Calif., assignor to Globe Oil Tools Company, Los Nietos, Calif., a corporation of California

Application June 17, 1933, Serial No. 676,357

16 Claims. (Cl. 255—71)

This invention relates to a rotary well drilling bit, and relates more particularly to a disk bit. It is a general object of the invention to provide a disk bit that is effective in operation and that is particularly simple and easy to assemble.

Another object of the invention is to provide a disk bit that includes a plurality of disk cutters rotatably mounted on a shank in a simple, practical and dependable manner.

Another object of the invention is to provide a disk bit of the character mentioned in which the cutters may be delivered to the field or well, assembled on their bearings so that they may be quickly and properly mounted on the body or shank of the bit.

It is another object of the invention to provide a disk bit that includes two inner disk cutters rotatably carried by a simple unitary bearing.

Another object of the invention is to provide a well drilling bit that includes two outer disk cutters rotatable on supporting bearings, two inner disk cutters rotatably carried on a unitary bearing, and a single member or pin retaining the bearings of the outer cutters on the shank and supporting the bearing of the inner cutters.

Another object of the invention is to provide a bit of the character mentioned having effective means for locking the removable bearing retaining and supporting pin in position.

A further object of the invention is to provide practical inexpensive, removable bearing units for carrying disk cutters.

Other objects and features of the invention will be best and fully understood from the following detailed description of typical forms and applications of the invention, throughout which description reference is had to the accompanying drawings, in which:

Fig. 1 is a partial vertical detailed sectional view of one form of the invention, being a view taken substantially as indicated by line 1—1 on Fig. 2. Fig. 2 is a transverse detailed sectional view taken as indicated by line 2—2 on Fig. 1. Fig. 3 is a side elevation of the body or shank embodied in the bit illustrated in Figs. 1 and 2. Fig. 4 is a side or end elevation of one of the outer disk cutters. Fig. 5 is a partial vertical detailed sectional view of another form of the invention. Fig. 6 is a side elevation of the bit illustrated in Fig. 5, and Fig. 7 is a diagrammatic vertical cross section of the lower portion of a well bore illustrating the action of the bit provided by the invention.

The form of the invention illustrated in Figs. 1 to 4 of the drawings includes, generally, a shank

or body 10, an inner cutter unit 11, two outer cutter units 12, and means 13 for detachably retaining the outer cutter units 12 on the body 10 and for removably supporting the cutting unit 11.

The shank or body 10 is a simple integral structure or member adapted to be attached to the lower end of an operating string of rotary drill pipe, or the like. Suitable means is provided on the upper end of the body 10 for facilitating attachment of the body with the drilling string. In the particular case illustrated in the drawings, a tapered screw-threaded socket 14 is provided in the upper end of the body 10 for receiving a pin on the drill collar or other part of the drilling string. The upper portion of the shank or body 10 may be cylindrical or of round cross section as illustrated throughout the drawings. The body 10 is provided with two downwardly projecting legs 15 to carry the cutter units 11 and 12. The legs 15 are preferably substantially vertical and have parallel vertical sides. In accordance with the invention, the two legs 15 are laterally offset as illustrated in Fig. 2 of the drawings so that a leading end of one leg relative to the direction of rotation of the bit is in advance of the trailing end of the other leg. The lower ends of the legs 15 may be curved or rounded. Projections or bosses 16 are provided on the outer sides of the legs 15. The bosses 16 are provided to carry the outer cutter units 12 and are of round cross section. The horizontal or longitudinal axes of the bosses 16 are normal to the outer sides of the legs 15. The bosses 16 are equally spaced between the opposite vertical ends of the legs 15 so that the two bosses 16 are horizontally offset or out of alignment. Recesses 17 are provided in the inner sides of the legs 15. Each of the recesses 17 has a straight vertical wall and a straight horizontal wall as clearly illustrated in Fig. 3 of the drawings.

The inner cutter unit 11 is mounted or positioned between the spaced legs 15 of the body and includes two substantially vertical disk cutters 18 and a bearing 19. It is a feature of the present invention that the two disk cutters 18 are rotatable on the single integral bearing 19. The bearing 19 is proportioned to effectively fit between the two legs 15 having flat opposite ends adapted to bear against the vertical walls of the recesses 17. An annular radial flange 20 is provided on the bearing 19. The flange 20 is preferably equally spaced from the opposite ends of the bearing. The bearing 19 is treated or hardened to be long wearing and to dependably carry the rotatable cutters 18.

The two disk cutters 18 of the inner cutter unit 11 are revolvable on the bearing 19 at the opposite sides of the flange 20 and have flat inner sides adapted to cooperate with the flange so that inward thrusts on the cutters are effectively transmitted to the flange. Hardened washers 21 surround the end portions of the bearing 19 to receive the outward thrusts from the cutters 18. The washers 21 seat or fit in the recesses 17 and have straight edges cooperating with the straight walls of the recesses so that they are held against rotation. The cutters 18 project below the lower ends of the legs 15 and are adapted to engage or act on the formation at the center of the bottom of the wall to form a central dished or concave depression or recess A. The bearing 19 is diametric of the axis of rotation of the bit, and as the cutters 18 are spaced apart by the flange 20, they may leave a very small central core or projection B of formation in the center of the recess A. In accordance with the broader aspects of the invention, any suitable form of cutting parts or edges may be provided on the cutters 18. In the particular embodiment of the invention illustrated in the drawings, series of cutting teeth 22 are provided on the peripheries of the cutters 11.

Dowel pins 23 extend through horizontal openings in the legs 15 and project into the recesses 17 to cooperate with recesses in the ends of the bearing 19 and washers 21 to prevent rotation of the bearing. The dowel pins 23 are readily removable to permit the easy removal of the inner cutter unit 11 as will be subsequently described. After the cutters 18 have been assembled on the bearing 19, the washers 21 may be attached or fixed to the bearing in any suitable manner to retain the cutters on the bearing so that the assembly of the bearing and cutters may be handled and transported as a unit. In practice, the washers 21 may be welded or otherwise fixed to the bearing 19. The outer sides of the cutters 11 may be bevelled inwardly from adjacent the peripheries of the washers 21 so as to have suitable clearance with the inner sides of the legs 15.

The outer cutter units 12 are carried or supported on the bosses 16 and each includes a disk cutter 24 and a removable or detachable bearing 25 for the rotatable cutter 24. The bearings 25 are tubular members adapted to be slid on to the bosses 16. The bearings 25 project outwardly beyond the ends of the bosses 16 and are provided at their outer ends with annular radial flanges 26. The inner ends of the bearings 25 may seat against the outer sides of the legs 15 as illustrated in Figs. 1 and 2 of the drawings. Thrust washers 27 are provided on the inner ends of the bearings 25 and are adapted to seat or bear against the outer sides of the legs 15. Dowels 28 project from the outer sides of the legs 15 and cooperate with notches or recesses in the washers 27 and bearings 25 to hold the washers and bearings against rotation. The washers 27 are welded or otherwise suitably fixed to the bearings 25. The bearings 25 and washers 27 are preferably hardened or heat treated.

The cutters 24 are rotatable on the bearings 25 and project downwardly below the lower ends of the legs 15 so as to act on the formation at the bottom of the well bore. In the particular case illustrated in the drawings, the cutters 24 have flat parallel sides. The inner sides of the cutters 24 bear against the washers 27 which space the peripheral portions of the cutters from the outer

sides of the legs 15. Annular recesses 30 are provided in the outer ends of the cutters 24 to receive the flanges 26 of the bearings. It will be apparent that outward thrusts on the cutters 24 are transmitted to the bearings 25 through the flanges 26. Cutting parts or edges are provided in the peripheries of the outer disk cutters 24. Any suitable or desirable form of cutting parts may be provided on the cutters. In the drawings I have illustrated the cutters 24 provided with helical or spiraled peripheral cutting teeth 31. The peripheries of the cutters taper outwardly so that the cutting edges of the spiraled teeth 31 taper or slope outwardly. The outer cutters 24 are preferably heavier and larger in diameter than the inner cutters 18. In operation, the outer disk cutters 24 are operable to make an annular cut C in the formation at the bottom of the well bore around the recess A. Due to the location of the cutters 24, the cut C has downwardly and inwardly curved walls extending from the cylindrical side walls of the well bore to the portion of the formation acted upon by the inner cutters 18. The outer cutters 24 project forwardly from the leading ends of the legs 15 and operate to cut or ream the well bore to size.

The means 13 for detachably retaining the outer cutter units 12 on the bosses 16 and for carrying the inner cutter unit 11 includes a pin 35 extending through horizontal openings 36 in the legs 15. The openings 36 are diametric of the axis of rotation of the bit and are accordingly eccentric of the bosses 16. The pin 35 extends through a central longitudinal opening 37 in the bearing 19 to support or carry the bearing and the cutters on the bearing. The removable pin 35 projects from the outer side of one leg 15 and its projecting portion carries a plate or head 38. The head 38 engages the outer end of the boss 16 and is welded or otherwise fixed to the pin 35. The head 38 is preferably of slightly less diameter than the washer 26 and its periphery is bevelled. A separable or detachable head 39 engages the end of the boss 16 on the other leg 15. The head 39 has a boss or lug 40 on its inner side extending into the pin carrying opening 36. The head 39 engages against the washer 26 to retain the cutter unit 12 on the boss 16 and is of substantially the same configuration as the head 38. In accordance with the invention, the head 39 is detachably connected to the pin 35. A cap screw 41 extends through an eccentric opening in the head 39 and is threaded into a longitudinal opening 42 in the pin 35. The screw 41 has a hollow head which is preferably counter-sunk in the plate or head 39. The invention includes means for removably or releasably locking the screw 41 in position. A flexible rod 43 is arranged against the head of the screw 41 and has an inner end part held in a recess 44 in the inner side of the head 39. When the screw 41 is threaded into the opening 42 of the pin, the rod 43 projects outwardly from the head 39. After the screw has been tightly threaded into position, the projecting end of the rod is bent into the hollow head of the screw to lock the screw in position.

The present invention includes means for flushing the cutters 18 and 24 and for maintaining an effective turbulence or circulation in the bottom of the well bore. A fluid chamber 45 is provided in the bottom or lower end of the socket 14 and a central fluid passage 46 extends through the body 10 from the chamber 45 to discharge between the legs 15 on to the inner cutters 18. Downwardly and outwardly inclined fluid discharge passages 75

47 communicate with the chamber 45 and discharge the circulation fluid downwardly and outwardly on to the cutting parts of the outer cutters 24. The passages 47 are located so as to discharge circulation fluid on to the forward or leading portions of the cutters 24. Downwardly and forwardly inclined fluid passages 48 extend through the legs 15 and discharge at the forward lower ends of the legs. The circulation fluid under pressure discharging from the passages 48 is effective in maintaining proper turbulence in the lower portion of the well bore. Choke pipes or nozzles 49 may be provided in the discharge end of each of the passages 46, 47, and 48.

15 In assembling the bit illustrated in Figs. 1 to 4 inclusive of the drawings, the assemblies of the inner cutters 18 and their bearings 19, and the assemblies of the outer cutters 24 and their bearings 25 are adapted to be handled as units. The inner disk cutters 18 are retained on the bearing 19 by the washers 21 so that the assembly may be readily handled without danger of displacement of the cutters. The outer cutters 24 are held on their respective bearings 25 by the washers 27 and flanges 26. When the cutters are to be mounted on the body, the bearing 25 carrying one of the cutters 24, is slid on to one of the bosses 16 and the pin 35 carrying the head 38 is passed into the opening 36. The inner cutter unit 30 is inserted between the legs 15 and held in position so that the pin 35 may be passed through the opening 37 in the bearing 19. After the pin 35 has been positioned so that its head 38 seats against the boss 16, the other outer cutter unit 35 12 is arranged on the other boss 16 and the head 39 is arranged against the boss 16 to lock the cutter unit in position. The screw 41 may then be threaded into the opening 42 and locked in place by the rod 43 in the manner described above. 40 The dowel pins 23 aid in positioning the inner cutting unit so that the opening 37 is in proper registration with the portions of the opening 36 in the two legs 15. It will be apparent how the cutter units 11 and 12 may be easily and quickly 45 secured in their proper positions on the bit. A simple wrench for engaging the screw 41 is the only tool required in the assembling of the bit. As the cutters 18 and 24 are assembled on their bearings at the place of manufacture, the proper fitting of the parts is assured.

50 In operation, the bit is rotated on the lower end of an operating string in the usual manner and the independently rotatable disk cutters 24 and 18 act on the formation at the bottom 55 of the bore. The outer cutters 24 project downwardly and forwardly from the legs 15 to cut the bore to size and to make the annular cut C in the bottom of the bore. The inner cutters 18, in being carried by the diametric bearing 19, project from the lower ends of the cutters 15 60 to cut the recess A in the formation. The heads 38 and 39 and the pin 35 are held against rotation by the relative eccentricity of the pin 35 and bosses 16. The end thrusts to which the 65 cutters 18 and 24 are subjected are effectively taken by the flanges and washers on the bearings 19 and 25 in the manner described above. The circulation fluid discharging from the fluid passage 46 is effective in the flushing of the inner cutters 18, while the fluid discharged from the passages 47 flushes the outer cutters 24. The bit is inexpensive and easy to assemble, and very effective in operation.

70 The form of the invention illustrated in Figs. 5 and 6 of the drawings includes a body 10^a, an

inner cutter unit 11^a, outer cutter units 12^a, and means 13^a for supporting the inner cutter unit 11^a and for detachably retaining the outer cutter units 12^a on the body.

The body 10^a is similar to the body 10 described above, having spaced projecting legs 15^a at its lower end. A tapered screw threaded pin 60 is provided on the upper end of the body 10^a to facilitate connection of the bit with the operating or drilling string. The legs 15^a have flat 10 vertical sides and are laterally offset in the same manner as the legs 15. The inner cutter unit 11^a is substantially identical with the cutter unit 11 including, an integral bearing 19^a and two disk cutters 18. The bearing 19^a fits between the two 15 legs 15^a and has a central radial flange 20^a. Washers 21^a are welded or otherwise fixed to the end parts of the bearing 19^a and seat in recesses in the inner sides of the legs 15^a. The cutters 18^a are rotatable on the bearing between the 20 flange 20^a and washers 21^a. The bearing 19^a is diametric of the axis of the bit and the cutters 18^a project from the lower ends of the legs 15^a to act on the formation at the bottom of the well bore. 25

The outer cutter units 12^a are supported on the bosses 16^a at the outer sides of the legs 15^a. Each outer cutter unit 12^a includes a bearing 62 and a cutter 24^a. The bushings or bearings 62 are threaded on the bosses 60^a and have closed 30 ends 63 covering the ends of the bosses. Outwardly projecting annular flanges 64 are provided on the outer end of each bearing 62 and a washer 65 is fixed on the inner end of each bearing and seats against the outer side of a leg 35 15^a. The disk cutters 24^a are rotatable on the bearings 62 between the flanges 64 and washers 65. The cutters 24^a project forwardly from the leading ends of the legs 15^a and downwardly from the lower ends of the legs. The outer cutters 40 24^a may be in the nature of plain disk cutters having smooth tapered peripheries and comparatively narrow peripheral cutting edges 66. The washers 65 and the bearings 62 to which the washers are attached may be held against rotation by dowels 67. 45

The means 13^a operates to removably retain the outer cutter units 12 on the bosses 16^a and to support the removable inner cutter unit 11^a. The means 13^a includes screws 70 passing through 50 concentric openings in the ends 63 of the bearings 62 and concentric openings 71 in the bosses 16^a. The inner ends of the screws 70 are threaded into openings 73 in the opposite ends of the bearing 19^a. The two openings 73 are eccentric so 55 that the bearing is positively held against rotation. Means is provided for locking the screws 70 in position. Lock washers or ear washers are arranged under the heads of the screws and each has one or more ears 75 cooperating with recesses 60 76 in the outer ends 63 of the bearings 62. Other ears 75 of the washers seat against the flat sides of the screw head to hold the screw against turning. 65

The body 10^a is provided with circulation passages for discharging circulation fluid to flush the cutters 18^a and 24^a and to maintain circulation in the bottom of the well bore. A vertical fluid passage 80 extends through the pin 60 and terminates in a chamber 81 in the body 10^a. A 70 central passage 82 extends downwardly from the chamber 81 and discharges fluid between the legs 15^a to flush the cutters 18^a. Downwardly and outwardly inclined fluid passages 83 extend from the chamber 81 and discharge from the exterior 75

- of the body at points above the outer cutters 24^a. Passages 85 extend downwardly through the body 10^a from the chamber 81 to discharge at the lower forward ends of the spaced legs 15^a. The 5 fluid discharging from the passages 86 maintains an effective turbulence and circulation in the bottom of the bore. Choke pipes or nozzles 86 may be provided in the discharge ends of the several fluid passages.
- 10 The operation of the bit illustrated in Figs. 5 and 6 of the drawings is the same as the operation of the bit illustrated in Figs. 1 to 4 inclusive. In assembling the tool, the bearings 62 carrying the cutters 24^a are first threaded on to the bosses 15^a. The inner cutting unit 11^a is then positioned between the legs 15^a so that its openings 73 register with the openings 71. The screws 70 are then passed through the openings 71 and threaded into the openings 73 to lock the bearings 62 in position and to support the inner bearing 19^a. The screws may be readily locked in place by bending the ears 75 of the lock washers into the recesses 76. It will be apparent how the cutter units 11^a and 12^a may be easily and quickly detached after removing the screws 70.
- 15 Having described only typical forms and applications of my invention, I do not wish to be restricted or limited to the specific forms and applications herein set forth, but wish to reserve to myself any modifications or variations that may appear to those skilled in the art or fall within the scope of the following claims:
- 20 Having described my invention, I claim:
1. A well drilling bit including, a body having 35 projecting legs on its lower end, bosses on the outer sides of the legs, a cutter unit positioned between the legs, cutter units supported on the bosses, and a single means supporting the first mentioned unit and retaining the other units on 40 the bosses.
2. A well drilling bit including, a body having projecting legs on its lower end, bosses on the outer sides of the legs, a cutter unit positioned between the legs, cutter units supported on the 45 bosses of the legs, and a single pin supporting the inner cutter unit and retaining the other units on the bosses.
3. A well drilling bit including, a body having 50 spaced legs projecting from its lower end, projecting bosses on the outer sides of the legs, removable disk cutter units on the bosses, an inner disk cutter unit positioned between the legs, there being aligned transverse openings in the legs and bosses, and a removable pin extending through 55 the openings and supporting the inner cutter unit and having heads retaining the first mentioned units on the bosses.
4. A well drilling bit including, a body having 60 spaced legs projecting from its lower end, a bearing between the legs having its ends bearing against the inner sides of the legs, a flange on the bearing between its ends, washers fixed on the end portions of the bearing, the washers having flat edge portions cooperating with correspondingly shaped parts on the legs to hold the bearing 65 against rotation, cutters rotatable on the bearing between the flange and washers, and means detachably supporting the bearing on the legs.
- 70 5. A well drilling bit including, a body having spaced legs projecting from its lower end, a bearing between the legs, bosses on the outer sides of the legs, bearings on the bosses, cutters rotatable on the bearings, there being openings in the legs and bosses eccentric to the bosses, a removable

pin extending through said openings and a longitudinal opening in the first mentioned bearing, and heads on the pin retaining the bearings on the bosses.

6. A well drilling bit including, a body having 5 spaced legs projecting from its lower end, a bearing between the legs, bosses on the outer sides of the legs, bearings on the bosses, cutters rotatable on the bearings, there being openings in the legs and bosses eccentric to the bosses, a removable 10 pin extending through said openings and a longitudinal opening in the first mentioned bearing, and heads on the pin retaining the bearings on the bosses, one of the heads being detachable to permit removal of the pin. 15

7. A well drilling bit including, a body, spaced downwardly projecting legs on the body, a removable one piece bearing between the legs having a radial flange between its ends, washers fixed to the bearing and spaced from the opposite 20 sides of the flange, cutters rotatable on the bearing between the flange and washers, and means removably supporting the bearing between the legs in a position where the cutters project downwardly below the ends of the legs. 25

8. A well drilling bit including, a body, spaced downwardly projecting legs on the body, the legs being laterally offset, bosses on the outer sides of the legs, removable bearings on the bosses, revoluble cutters retained on the bearings, a removable bearing between the legs having a longitudinal opening, a revoluble cutter on the last named bearing, there being openings in the legs and bosses diametric of the axis of rotation of the body and eccentric of the bosses, a removable 35 pin extending through the last mentioned openings and the opening in the said bearing, and means on the pin for retaining the first mentioned bearings on the bosses. 30

9. A well bit including, a body, spaced legs 40 projecting from the body having projecting bosses on their outer sides, bearings threaded on the bosses, the bearings having ends covering the ends of the bosses, cutters rotatable on the bearings and projecting beyond the lower ends of the 45 legs, there being transverse openings in the legs extending through the bosses, a removable cutter carrying bearing between the legs, and screws engaging said ends of the bearings passing through said openings and threaded into eccentric openings in the last mentioned bearing to lock the first mentioned bearings on the bosses and to support the last mentioned bearing. 50

10. A well bit including, a body, spaced legs projecting from the body having projecting bosses 55 on their outer sides, bearings threaded on the bosses, rotatable cutters on the bearings and projecting beyond the lower ends of the legs, there being transverse openings in the legs extending through the bosses, a removable cutter carrying 60 bearing between the legs, and members passing through said openings and threaded into eccentric openings in the last mentioned bearing to support it and engaging the first mentioned bearings to lock them on the bosses. 65

11. In a well bit, a body, spaced legs projecting from the lower end of the body, there being recesses in the inner sides of the legs, having flat wall portions, a removable bearing between the legs having its ends bearing against the inner 70 walls of the recesses, washers rigidly attached to the bearing and having flat faces cooperating with said flat wall portions of the recesses to hold the bearing against rotation, means removably supporting the bearing, and a cutter rotat- 75

able on the bearing and projecting from the lower ends of the legs.

12. In a well bit, a body, spaced legs projecting from the lower end of the body, there being recesses in the inner sides of the legs having flat wall portions, a removable bearing between the legs having its ends bearing against the inner walls of the recesses, washers rigidly attached to the bearing and having flat faces cooperating with said wall portions of the recesses to hold the bearing against rotation, a radial flange on the bearing spaced between the washers, cutters rotatable on the bearing between the flange and washers and projecting beyond the lower ends of the legs, and a removable member supporting the bearing.

13. A rotary well bit including, a body, two spaced legs projecting from the lower end of the body, the legs being laterally offset in the direction of rotation of the body, projections on the outer sides of the legs, removable bearings on the projections, disk cutters on the bearings projecting from the lower ends of the legs and rotatable about axes laterally offset in the direction of rotation of the body to project forwardly beyond the leading edges of the legs, and spaced disk cutters between the legs rotatable on an axis diametric of the axis of rotation of the body and projecting beyond the lower ends of the legs.

14. A rotary well bit including, a body, two spaced legs projecting from the lower end of the body, the legs being laterally offset in the direction of rotation of the body, projections on the outer sides of the legs, removable bearings on the projections, disk cutters on the bearings projecting beyond the lower ends of the legs and

rotatable about axes laterally offset in the direction of rotation of the body to project forwardly beyond the leading edges of the legs, a removable bearing between the legs having a longitudinal axis diametric of the axis of rotation of the body, a radial flange on the bearing lying in the plane of the axis of rotation of the body, and a disk cutter rotatable on the bearing at each side of the flange and projecting downwardly below the lower ends of the legs.

5

10

15. A rotary well bit including, a body, two spaced legs projecting beyond the lower end of the body, the legs being laterally offset in the direction of rotation of the body, projections on the outer sides of the legs substantially equally spaced between the leading and trailing edges of the legs, removable bearings on the projections, rotatable cutters on the bearings projecting beyond the lower ends of the legs and forwardly beyond the leading edges of the legs, a removable bearing between legs, a cutter rotatable on the bearing and projecting downwardly beyond the lower ends of the legs, and means retaining the bearings on the legs so that the assemblies of the bearings and cutters are replaceable as units.

25

16. A well drilling bit including a body having projecting legs on its lower end, a projecting boss on the outer side of a leg, a removable bearing on the boss, a cutter rotatable on the bearing, a bearing between the legs, a cutter rotatable on the second mentioned bearing, and a removable member holding the first mentioned bearing against displacement from the boss and supporting the second mentioned bearing.
